LORENZ BOMMER, OF NEW YORK, N. Y.

Letters Patent No. 83,597, dated November 3, 1868.

IMPROVEMENT IN BLOCKS AND DIES FOR FORMING HATS.

The Schedule referred to in these Letters Patent and making part of the same.

To all whom it may concern:

Be it known that I, LORENZ BOMMER, of the city, county, and State of New York, have invented a new and useful Improvement in the Process of Making Hat-Blocks, Moulds, and Dies, of porous stone, or similar substances; and I do hereby declare that the following is a full, clear, and exact description thereof.

Hat-blocks, moulds, and dies have been made, and are now made, of iron, plaster of Paris, wire gauze, &c., on which hats, hat-bodies, boxes, and such like articles, are made, of buckram, and other woven fabrics, felt-cloth, leather, paper-pulp, &c.

The wovens and such like material, when used, is generally wet or dampened, that it may the more readily be stretched to the shape required, and hot metal dies have been used to strike up such articles into shape, but the great difficulty has been to dry the articles after being thus formed, and have them keep the proper shape.

In using the iron or plaster blocks, the dampness cannot pass off except through the material, and when the iron-blocks are heated, it passes off as steam, and takes, under any circumstances, a long while to dry.

In forming hats of leather on plaster blocks, the dampness which cannot pass off, stains the leather, and renders the hats worthless.

Hats and other articles have also been formed, and are now formed, of pulp in porous moulds, which permit the water to filter through, and which retain the fibres until accumulated to the required thickness. Such moulds have heretofore been made of wire gauze, but as the wire cannot be woven to the form required for such moulds, the gauze has to be united in places, so that the seams leave marks on the articles moulded therein.

Another objection to the use of such moulds arises from the fact that the wire gauze, which must be made of very fine wire, is not sufficiently strong to resist the pressure to which they are subjected in the operation of moulding hats and other articles, and for that reason the wire-gauze mould has to be sustained by an outer lining of perforated metal, the perforations in which cannot be made so fine as or to correspond with the meshes of the wire gauze.

It is desirable, in making hats, &c., from pulp, to allow the articles thus formed to dry in the moulds, but this method has not been practised to advantage, because of the expense of having on hand so large a number as would be required in manufacturing on a large scale, and, in consequence, such moulds have been used simply to form the hats in, which, so soon as formed, are taken out to dry in the open air, or in the drying-room, and are then pressed in other moulds.

The object of my invention is to produce blocks and moulds for the above purposes, which will avoid the defects above pointed out, and to this end my said invention consists in making moulds and blocks for making hats, &c., of pulp and other materials, by the process of filtration of porous artificial stone or equivalent substances, by which I am enabled to obtain a suitable moulding-surface, and at a cost so trifling, compared with those now used, that, if desired, the manufacturer can have on hand a sufficient number of them to allow the hats, &c., to remain in them until thoroughly dry, and, if desired, they can be made of sufficient strength to admit of pressing the hats, &c., therein or thereon.

To facilitate the filtering and drying, I can remove the dampness from the articles through the blocks by suction, which will render them dry almost immediately.

By my invention the blocks or dies are moulded into any required shape, and may be used in connection with hot dies, if necessary. The articles thus formed may be on the outside or inside of the blocks, and in either case the dampness or steam passes off by filtration and evaporation through the moulds or blocks, and the material is left dry and in the required shape, which cannot be the case with those now in use, or when the articles are dried in the open air or drying-room.

The porous material which I have used with success for the making of my improved moulds and blocks is that described in Letters Patent, granted to F. C. Krause on the 17th day of February, 1863, for an improved compound for porous stone, which compound is prepared by mixing from four to six pounds of sand and from three to six ounces of marble-dust with one pound of silicate of soda or potash, a sufficient quantity of water being added to bring the compound to a plastic state, so that it can be moulded to the required form, and then heated in a kiln to a high white heat.

The compound above described, I prefer for the making of my improved blocks, moulds, and dies, but I do not wish to be understood as limiting my claim of invention to the use thereof, as other and equivalent compounds and materials may be substituted.

What I claim as my invention, and desire to secure by Letters Patent, is—

Making porous hat-blocks, moulds, and dies, substantially as described, as distinguished from moulds made porous by perforations or woven meshes.

LORENZ BOMMER.
